UNITED STATES PATENT OFFICE.

MICHAEL J. MCGOWAN, OF CHICAGO, ILLINOIS.

HAIR WAVER.

Application filed May 28, 1927. Serial No. 195,112.

This invention relates to a hair waving device particularly for use on bobbed haired women.

The main objects of this invention are to provide a device for producing marcel and other forms of waves in women's hair; and to provide a device of this kind that can be used by unskilled persons on their own hair.

An illustrative embodiment of this invention is shown in the accompanying drawings, in which:

Fig. 1 shows the hair waving device in place on a person's head.

Fig. 2 is an enlarged fragmentary plan view of a portion of the device.

Fig. 3 is an enlarged detail in perspective of one of the combs which engages the hair.

Fig. 4 is a fragmentary detail in perspective of one of the elastic comb retaining cords.

Fig. 5 is a similar view, showing a pair of the elastic cords and the fastening means for the opposite end of a comb.

In this improved invention, a head harness is provided, which comprises a pair of main supporting straps, one to be disposed around the forehead, down the cheeks, and under the chin of the user, and the other main band extending from the chin ends of the first mentioned band diagonally backward across the back of the head at the upper part thereof. These two bands are joined by a narrow strap, which is disposed so as to lay along the line where the hair is parted. A plurality of combs having inwardly disposed teeth are placed in the hair, and then adjacent combs are shifted longitudinally in opposite direction to form the desired waves or swirls, the ends of the combs being supported and attached to the head harness main bands.

In the construction shown in the drawings, the hair waver comprises a head harness having a front supporting band 1, formed in a loop and shaped so as to fit across the forehead at the front edge of the hair line and down the cheeks of the user in the form of a loop. The lower ends of the band overlap underneath the chin of the user, and are secured together by strings 2, which are stitched or otherwise suitably secured to the supporting band 1 near the ends thereof.

A second main supporting band 3, has its ends secured to the ends of the band 1 at a

point closely adjacent the chin of the user, and forms a loop which extends diagonally backward to pass over the back part of the head near the upper part thereof. The medial parts of the bands 1 and 3 are attached together by a narrow band 4, which is disposed so as to lay along the line where the hair is parted.

The hair engaging and waving parts of this device comprise a plurality of combs 6 of varying length, which are arranged in a suitable curve so as to conform to the curvature of the user's head. The combs are preferably formed by having a double parallel row of short inwardly disposed teeth 7 of sufficient length to extend through the hair and contact with the scalp of the user. One end of the comb 6 is provided with an integrally formed hook 8 for attachment of the comb to the head harness, and the other end is provided with a plurality of integrally formed longitudinally spaced similar hooks 9 for providing adjustable attachment.

Means are provided for attaching the combs to the head harness, and comprise elastic cords 10, 11 and 12, carried on the supporting bands 1 and 3. The elastic cords are carried on the supporting bands by stitching thereto relatively narrow strips of material 15 along their marginal edges, with the middle part thereof slightly gathered so as to form a channel in which the elastic cords are free to slide or otherwise move therein. At suitable points along the strip 15, stitching is omitted and a loop of the cord is allowed to extend out through this opening, as shown particularly in Fig. 4. The front supporting band 1 carries a single elastic cord, and the back supporting band 3 is provided with a pair of these cords arranged side by side, as shown particularly in Fig. 5 of the drawings.

At suitable points along the supporting bands, that is, at every alternate point of attachment of the combs, the strip 15, which is of semi-rigid material is looped upwardly, as at 20, for receiving the end of the comb 6, which has the hooks 9 thereon.

In the use of this hair waving device, the hair is first wet with water or suitable hair curling fluid and the head harness without the combs is placed upon the head of the user and tied thereon with the narrow strip 4 laying along the line where the hair is

parted. A comb 6 is then placed on the head with the teeth 7 passing down through the hair and contacting with the scalp of the user, and with the hook 8 engaged in a loop 5 of the elastic cord 10. The comb is then shifted longitudinally, stretching the loop of the elastic cord, as shown in dotted lines in Fig. 2, and the opposite end of the comb passed through the upstanding loop 20, one 10 of the hooks 9 engaging with the top of the loop 20 to hold the comb in such shifted position.

The next comb 6 is then attached and placed in position in the same manner, except that such next succeeding comb has the 15 ends thereof reversed with relation to the first comb and it is shifted in the opposite direction, thereby producing the wave or swirl desired in the hair.

20 A series of these combs are provided for fitting between the supporting bands along both sides of the head, and also for fitting around the back of the head, so that the 25 wave or swirl formed by the combs is continuous around the head from one side to the other.

Although but one specific embodiment of this invention has been herein shown and described, it will be understood that numerous 30 details of the construction shown may be altered or omitted without departing from the spirit of this invention as defined by the following claims.

I claim:

1. A hair waving device comprising spaced supporting members adapted to be secured to the head of a user, a series of hair engaging combs attached to said supporting members and spanning the space therebetween, and means for permitting longitudinal shifting of said combs in alternate directions with respect to each other. 35

2. The method of waving hair comprising the placing of a supporting harness on the head of the user, resiliently attaching a plurality of hair engaging combs to said harness in substantially parallel relationship, shifting said combs longitudinally in alternate directions for waving the hair, and then fastening said combs in such shifted 40 position. 45

3. A hair waving device comprising spaced supporting members adapted to be secured to the head of the user, resilient comb attaching means carried by said members, a plurality of combs having one end detachably connected with said resilient attaching means, said combs being adapted to engage the hair of the user and to be shifted longitudinally to form waves therein, and means on said supporting members for engaging the opposite ends of said combs for retaining them in such shifted position. 55

Signed at Chicago this 19th day of May 1927.

MICHAEL J. McGOWAN.
